UNITED STATES PATENT OFFICE.

EDWARD C. VAN GLAHN, OF NEW YORK, N. Y., ASSIGNOR TO NATIONAL ELECTRIC UTILITIES CORPORATION, OF NEW YORK, N. Y., A CORPORATION OF NEW YORK.

UNIT OR GRID.

1,088,114.

Specification of Letters Patent.

Patented Feb. 24, 1914.

Application filed September 19, 1913. Serial No. 790,618.

To all whom it may concern:

Be it known that I, EDWARD C. VAN GLAHN, a citizen of the United States, residing at the city of New York, in the county 5 and State of New York, have invented new and useful Improvements in Units or Grids, of which the following is a specification.

This invention relates to heating units or grids for use in electric ranges, ovens and 10 similar cooking and heating devices, and it comprises simple and efficient means for supporting the heating element, whereby the usual numerous insulators heretofore employed may be dispensed with and whereby 15 the supporting means may be removed to substitute new ones without the necessity of removing the heating element.

Electric grids, particularly for large furnaces and ovens, must be of especially strong 20 construction to provide against melting and warping due to the intense heat to which they are subjected. The frame and radiating surface must be thoroughly electrically insulated from the heating element, which is 25 usually in the form of coiled wire. In heretofore known electric grids, so far as I am aware, the heating element is usually supported from a large number of binding 30 posts secured in a plate carried by the frame. Frequently more than one hundred such 35 posts are necessary for a grid 25x17 inches, and each such post must be insulated from the plate. Usually mica disks or other form of insulation is employed, but, because of 40 the construction, the posts frequently become grounded or short-circuited, and it is then necessary to substitute a new one. To 45 do this in such heretofore known grids, the element wire must be completely unstrung and new posts secured in place on the plate and the element wire restrung to position 50 through all the posts or supports. This involves considerable loss of time and is an expensive method of repairing. Furthermore, because of the construction, there is a great tendency for the grids to warp.

The present invention has for its objects 55 the production of a heating unit or grid which obviates the disadvantages of the heretofore known grids and which is very strong and durable and comparatively inexpensive in construction.

Another object of the invention is the

provision of a grid having relatively few number of parts and being as light in 55 weight as is consistent with the requisite strength.

While it has the advantage of being of the radiant heat type, fully exposed to the air on both sides, it can be completely inclosed by the use of baffle irons or other sheet metal covering and by the use of any material to reflect heat its efficiency may be correspondingly increased.

The invention comprises a frame made 65 preferably of angle iron with a plurality of transverse supports, preferably of T-iron construction or bars having flanges, and arranged in such manner as to provide for expansion and contraction of the metal, and 70 having means such as seats for the reception and retention of insulating element supports preferably in the form of bushings of porcelain, electrobestos, lava or other insulating material. The heating element of 75 carbon or in the form of coiled wire is threaded through the bushings and suitably connected to different terminals whereby it may be used to furnish several different heats. Specifically the supporting irons are 80 made in complementary halves and are arranged to be removably secured to the frame; and specifically the insulators are made of two complementary sections in order 85 that they may be inserted in place around the element wire without the necessity of stringing or threading the wire through them. This construction is very advantageous if for any reason it is desired to repair the grid, for instance, by replacing an accidentally broken insulating bushing. By this construction the heating element is completely exposed allowing thorough circulation and all danger of grounding or short-circuiting is completely eliminated; whereas, in the old type of grids heretofore referred to, the heating element is not exposed, because it is inclosed by the supporting plate for the posts and, because of the construction and number of posts used, the 100 liability for short-circuiting is very great. The loose connection of the bars to the grid frame and the loose engagement of the thimbles in their seats constitute important parts of my invention, as the former arrangement 105 prevents warping and buckling of the frame

and the latter arrangement prevents breakage of the thimbles due to unequal expansion.

In the accompanying drawings showing 5 one form of a specific embodiment of my invention and in the several views of which similar reference characters designate corresponding parts, Figure 1 is a top plan view of a complete grid; Fig. 2 is a transverse 10 section along line 2-2 of Fig. 1 on an enlarged scale; Fig. 3 is a view similar to Fig. 2, showing the upper T-iron separated and without the element supports; Fig. 4 is an enlarged longitudinal section along line 15 4-4 of Fig. 1; Fig. 5 is a detailed perspective of one form of bushing or thimble; and Fig. 6 is a transverse section through another form of thimble which is advantageous when repairing the grid.

20 In the form of invention here shown, for the sake of exposition, 1 indicates a frame preferably of angle iron having along one longitudinal side 2 the spaced slots 3, corresponding in number to the number of supports or bars for the bushings. The opposite longitudinal side 4 of the frame is provided with the same number of spaced slots 5 for the bushing supports. These supports 6 are bent at one end with the right-angle 25 portion 7, which is arranged to be inserted in the slots 5, when the support may then be brought parallel with the frame, whereupon the flange 8 on the opposite extremity is inserted in the slot 3 and a cotter-pin 9 30 passed through the hole in the flange to retain the support in position. The under side of the frame is provided with a corresponding number of T-irons 10, either permanently or removably secured in the frame by 35 means of the slots and tongues 11.

The upper and lower thimble supports are provided with complementary recessed portions 12, corresponding to the contour of the bushings to be employed and forming 40 seats for them. When the apparatus is first constructed, the bushings are preferably integral and are placed in the seats 12 and located in position by the upper supports 6 and their seats and the element wire is 45 then threaded through them; but when it is desirable to replace a bushing for any reason, those shown in Figs. 5 and 6 may be employed.

50 13 designates a solid bushing used when the apparatus is first assembled.

55 14 designates one form of a split bushing or thimble, and 15 designates a still different form. The thimble 15 is provided with a tongue and groove 16 to prevent lateral displacement of the complementary halves.

60 The arrangement of heating element 17 having the two terminals 18 and 19 and bus-bar 20 is not a part of my invention, except in combination with the improved insulator supports which adapt it for advantageous

use in a grid, and I do not claim such arrangement herein.

Because of the tendency of the apparatus of the present to warp in use and to expand, provision is made to prevent such warping 70 and expansion having deleterious influence upon the bushings. The supports for the bushings are preferably arranged to loosely engage them and to leave room for the unequal expansion and contraction of the metal 75 of the bars and of the porcelain, electro-asbestos, lava or other material of the bushings.

I do not limit my invention to the exact construction shown, as many different forms 80 embodying the invention may be availed of. I consider myself entitled to the general construction and arrangement of parts as shown without limitation to the specific arrangement and construction and the use of 85 particular material.

What I claim is:—

1. An electric grid comprising a main support, a plurality of sets of spaced transverse supports carried by the main support, 90 each set comprising complementary halves having insulator seats therein, insulators in said seats, at least one half of each of said sets being independently removable from its associated half whereby the insulators of one set of supports may be accessible without disassembling the other supports, and a heating element carried by said insulators. 95

2. A grid comprising a frame having a series of spaced slots on opposite sides, a 100 plurality of lower cross-bars having seats for insulators, a plurality of upper cross-bars having insulator seats corresponding to the insulator seats of the lower bars and having at opposite ends, means for engagement with the slots of the said sides, insulators maintained in said seats by said cross-bars, and a heating element supported in the frame by said insulators. 105

3. An electric grid comprising a frame 110 having means on opposite sides for maintaining insulator retaining means in position, a plurality of lower transverse insulator supports carried by said frame, a plurality of upper insulator retaining means 115 having opposite ends adapted for engagement with the means of said frame, a plurality of independent insulators removably secured in the frame through said insulator retaining means and said supports, and a 120 heating element supported in said frame by said insulators.

4. An electric grid comprising a frame, a plurality of lower T cross-bars having insulator seats therein, a plurality of upper 125 T cross-bars having insulator seats therein, a plurality of insulators, each located between said bars and in said seats, and a heating element supported by said insulators. 130

5. An electric grid comprising a main support, a plurality of lower bars having upwardly projecting flanges with insulator seats therein, a plurality of upper bars having downwardly projecting flanges with insulator seats therein, at least one set of said bars being removably secured to said frame, a plurality of insulators, each located between said flanges in said seats, 10 and a heating element supported by said insulators.
6. An electric grid comprising a main support having means on opposite sides for temporarily securing insulator retaining means in position, a plurality of sets of insulator retaining means carried by said frame and secured by the means on the frame, insulators carried by said retaining means, and a heating element carried by 15 said insulators, at least one set of said insulator retaining means being arranged so that it may be removed.
7. In a grid, a frame of angle iron, a set of transverse bars secured to the vertical side of said angle iron, and having means for maintaining insulators in place, another set of transverse bars secured to the horizontal sides of said angle iron and having means for retaining insulators in place, insulators in said means, and a heating element supported in said frame by said insulators.
8. An electric grid comprising a frame, cross-bars having flanges with seats there-
- in, individual insulators in said seats, and 35 a heating element supported by said bars through said insulators.
9. An electric grid comprising a frame, a plurality of lower cross-bars having upwardly projecting flanges with insulator 40 seats therein, a plurality of corresponding upper bars having downwardly projecting flanges with insulator seats therein, a plurality of insulators each located between said flanges and in said seats, and a heating element supported by said insulators.
10. An electric grid comprising a rigid frame of angle-iron, members secured thereto at opposite ends for supporting insulators, hollow insulators carried by said 50 members, and a heating element carried by said insulators.
11. An electric grid comprising a rigid angle-iron frame, element supports loosely connected thereto, a heating element supported by said supports, and insulators for 55 said heating element.
12. In an electric grid, supports for a heating element and insulators carried by said supports, said insulators comprising 60 split thimbles having interlocking portions.
- In testimony whereof, I have hereunto set my hand in the presence of witnesses.

EDWARD C. VAN GLAHN.
